CLAIM

The ornamental design for a car sunroof accessory, as shown and described.

DESCRIPTION

FIG. 1 is a front, right and bottom perspective view of a car sunroof accessory, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 6.

The broken lines in FIGS. 6 and 9 illustrate the periphery of the enlarged views of the car sunroof accessory and form no part of the claimed design.

1 Claim, 9 Drawing Sheets
